COMBINATION TRUNK AND SAMPLE-CASE.

1,110,020.

Specification of Letters Patent.

Patented Sept. 8, 1914.

Application filed June 28, 1911. Serial No. 635,824.

To all whom it may concern:

Be it known that I, SAMUEL T. WHITAKER, a citizen of the United States, residing at Columbus, in the county of Muscogee and State of Georgia, have invented certain new and useful Improvements in Combination Trunks and Sample-Cases; and I do hereby declare the following to be a full, clear, and exact description of the invention, such as will enable others skilled in the art to which it appertains to make and use the same.

This invention relates to improvements in combination trunks and display cases, and has for an object the arrangement of receptacles in nested relation within a housing, the construction being such as to adapt the receptacles when closed to be readily and quickly withdrawn and exposed to view for displaying their contents.

With this and other objects in view, the invention comprises certain novel constructions, combinations and arrangements of parts as will be hereinafter set forth and claimed.

In the accompanying drawings.—Figure 1 is a top plan view of an embodiment of the invention, the parts being shown in their open or display position. Fig. 2 is a vertical, central section taken approximately on the plane indicated by line 2—2 of Fig. 1. Fig. 3 is a similar section taken substantially at right angles to the plane of section of Fig. 2, and showing the parts in their folded or closed position. Fig. 4 is a vertical section taken approximately on the plane indicated by line 4—4 of Fig. 3.

Referring to the drawings by numerals, 1 indicates a casing or housing having a bottom 23, sides 24, 24, and ends 26, 26. Supplemental end pieces 6, 6, are arranged within the housing or casing 1 and against the respective ends 26. Each supplemental end piece 6 is formed with spaced vertical guiding grooves 5, 5, and interposed between the grooves is a guiding strip 9 adapted to supplement the guiding of the parts hereinafter described. The strips 9 are arranged about midway of the supplemental end pieces 6 and the grooves 5 are spaced at either side thereof, said grooves terminating short of the upper end of the respective piece 6, and above the strips 9 is arranged a longitudinal plate or retaining strip 2 fixed at its ends to the upper ends of the

plates 6. The ends 26 terminate below the upper ends of pieces 6 for accommodating parts of the cover hereinafter described, and the side pieces 24 are cut away as at 25, 25, so that their upper edges are disposed below the plane of the upper edges of the ends 26, each of the cut away portions being of a depth substantially equal to the depth of a drawer-like receptacle 10, there being two of the receptacles 10, of a depth equal approximately to the width of the space between the respective side 24 and the nearest edge of the plates 9, so that the two receptacles are adapted to be accommodated within the housing and between plates 9, and the respective sides, when the receptacles are in a vertical position. Pins 7, 7, extend from each receptacle 10 near their inner or rear corners and project into the guiding grooves 5 for directing the receptacles in their movement.

A tray 14 is adapted to be nested within each receptacle 10 and each tray is connected to its respective receptacle by links 18, 18, slidingly engaging retaining studs or pins 19, 19, projecting inwardly from the respective receptacle 10 and similar pins or studs 20, 20, extending outwardly from the respective trays 14, the links being thus free to swing and the studs being free to travel longitudinally of the links for allowing the trays to have a swinging and sliding movement from the nested position such as seen in Figs. 3 and 4 and also as indicated in dotted lines at the right of Fig. 2 to an extended position such as seen in full lines in Figs. 1 and 2. The inner edge portion of each tray 14 is preferably provided with a stop or supporting block 16, and a similar block 12 is arranged within each receptacle 10 adjacent the outer edge thereof for supporting the outer edge portion of the tray when the tray is in its closed position. The blocks 12 and 16 are of a width adapting the tray to fit within the receptacle with its upper or open edge substantially flush with or slightly inside of the corresponding edge of the respective receptacle 10. A tab 27 is fixed to the outer edge portion of each tray 14 and extends in position for facilitating operation of the parts. The tabs 27 may, of course, be made of any suitable material, preferably flexible, to enable the desired nesting of the tray within the respec-

tive receptacle while the tab extends beyond the edge of the receptacle for the purpose of being grasped manually.

The top or cover of the housing 1 consists of two tray-like cover plates 22 having depending side plates or flanges 17, 17, of a width sufficient to have their lower edges rest on the upper edges of the cut-way portions 25 when the cover plates are in their closed position. The outer end of each cover plate 22 is provided with a flange 8 which is of less width than the side flanges 17, and the opposite end of each cover plate is provided with a still narrower flange 13. Eyes 36 are fixed to and outstand from the upper portion of each supplemental end piece 6, and a pintle or hinge rod 35 is arranged for each end piece and extends through said eyes and is carried thereby, each of said rods in turn pivotally sustaining a hinge leaf or plate 34. Each plate or leaf 34 is formed with apertures 33, and through said apertures loosely extend parallel rods 32, 32, which rods have their ends fixed to the flanges 8 and 13 of the respective cover plates 22. Thus the cover plates 22 are capable of being slid apart horizontally longitudinally of the housing, the rods 32 moving longitudinally through the apertures 33 in hinge plates 34 until the flanges 13 strike plates 34. Thereupon the leaves 34 may be hinged outwardly, the plates 22 being thus lowered pivotally from a horizontal to a vertical position and may hang thus vertically outside of the ends 26, or the cover plates 22 may be removed from their closed position by being swung pivotally in the first instance, the plates 34 swinging as hinges and the cover plates being swung until they arrive in a horizontal, inverted position with their former inner flanges outermost, as indicated in Fig. 1. In this position the cover plates with their flanges may serve as trays, and the weight of the outstanding parts of the cover plates is sustained by a shearing stress on the rods 32 transmitted thence to the hinge leaves 34 and their connected parts.

A latch or locking device of any appropriate type, as indicated at 37, may be provided for retaining the cover plates 22 in their closed position.

In operation, assuming the parts to be in the position indicated in Figs. 3 and 4, the cover plates are first removed in either of the two ways above suggested, and then the operator grasps the upwardly projecting end of one of the tabs 27 and draws the same upwardly which produces an upward sliding movement of the respective receptacle 10, the pin 7 traveling in the respective grooves 5 until the pins contact with the upper ends of said grooves. When the parts arrive at this position, the operator swings the upper edge of the receptacle 10 out-

wardly, moving the same on the pins 7 as a pivot, until the receptacle rests on the upper edge of the respective side 24, the cut-away portion 25 being sufficiently deep to accommodate the receptacle in a horizontal position, and the distance between the inner edge of the receptacle and the edge of the side 24 being less than the distance between said side and the outer edge of said receptacle so that the balance of weight will normally be beyond the side and hence the receptacle will rest in the position given it, being retained against tilting outwardly by engagement of the pins 7 with the ends of the slots 5 and also by engagement of the upper inner edge of the respective receptacle with the under face of plate 2. The parts having arrived at this position, and the operator still holding on to the tab 27, lifts the same upwardly until the outer edge of the respective tray arrives above the upper outer edge of receptacle 10, and then the operator draws the tray 14 outwardly to the limit of its movement prescribed by links 18 and their connections, whereupon the particular receptacle and tray will be in the position indicated in Fig. 2. The other receptacle and tray may be moved to their open or unfolded position in exactly the same manner. The closing of the tray and receptacle consists of the reverse movement including the replacing of the tray in the receptacle 10, a pivoting of the receptacle to a vertical position, and then a sliding of the receptacle downwardly into the housing, the pin 7 guiding the receptacle in such downward movement. It is noted that the grooves 5 are merely illustrative guide-ways and other guide-ways and guiding means may be provided, but such guide-ways must be so arranged as to permit the swinging of the receptacle from a vertical to a horizontal position.

It is to be observed that the movement of withdrawing the receptacle and its tray may be accomplished with the utmost facility and speed, as the movement is practically one continuous motion consisting of elevating the receptacle, swinging it over to a horizontal position, and elevating and drawing out the tray. Thus no time whatever is lost in exposing the contents of the receptacles and the tray, the contents of the receptacle, of course, being disposed between the tray and the bottom of the receptacle in the space provided for by the stops 12 and 16.

What I claim is:—

1. In a device of the class described, the combination of a casing having guiding means, and a receptacle having co-operating means engaging the guiding means of the casing for enabling bodily reciprocal and pivotal movement of the receptacle, the casing being formed with a cut-away portion

in one of its walls sufficient for causing the upper edge of the wall at the cut-away portion to lie in a plane below the plane of the upper edge of the guiding means 5 of the casing a distance substantially equal to the depth of the receptacle, and the receptacle being adapted to be swung laterally from a vertical position when its co-operating guiding means is at the upper 10 terminus of the guiding means of the casing to a substantially horizontal position in contact with the upper edge of the wall at the cut-away portion.

2. In a device of the class described, the 15 combination of a casing, a plate at the upper portion of the casing, and a receptacle movably mounted in the casing and adapted to be moved vertically in part past the plate and to swing from the vertical position laterally 20 to a substantially horizontal position with its inner edge beneath the plate and its outer portion resting on a portion of the casing, the portion of the casing thus engaged by the receptacle being disposed in a plane a distance below the under face of the plate substantially equal to the depth of the receptacle.

3. In a device of the class described, the 30 combination of a casing, a plate at the upper portion of the casing, and a receptacle movably mounted in the casing and adapted to be moved vertically in part past the plate and to swing from the vertical position lat-

erally to a substantially horizontal position with its inner edge beneath the plate and its 35 outer portion resting on a portion of the casing, the portion of the casing thus engaged by the receptacle being disposed in a plane a distance below the under face of the plate substantially equal to the depth of the 40 receptacle, said receptacle extending beyond the portion of the casing on which it rests a distance greater than the distance between such portion of the casing and the inner edge of the receptacle.

4. In a device of the class described, the combination of a casing, and a receptacle bodily movably mounted therein, the casing being formed with guide-ways disposed laterally with respect to the receptacle and the 50 receptacle being formed with guiding pins projecting laterally into said guide-ways and adapted to enable vertical reciprocation of the receptacle limited in an upward direction by the engagement of the pins with the 55 guide-ways, the said receptacle being adapted to be swung thence on the pins as a pivot to a horizontal position resting on a portion of the casing.

In testimony whereof I affix my signature 60 in presence of two witnesses.

SAMUEL T. WHITAKER.
